HARRY E. CAMPBELL, OF BALTIMORE, MARYLAND

SASH HAVING RESILIENT EDGE PORTIONS

Application filed December 19, 1928. Serial No. 326,938.

In windows of the type in which the jambs have vertical openings in their inner face behind which are enlarged chambers and the sashes have plates which extend through said openings and strike against the backs of the chambers to limit transverse movement of the sashes, difficulties sometimes occur due to the jamb frame being distorted while being erected, which means that the sashes have to be provided with some form of adjusting device such as shown in my earlier Patent No. 1,502,644 dated July 22, 1924, and these adjusters have to be properly set after the window frames are installed. According to the present invention I overcome this difficulty by forming the sashes with stiff but resilient edges. To accomplish this result a U-shaped member is slipped over the edge of the sash so that it forms substantially a continuation of the sash plate. This U-shaped member is held to the sash in such a way that it moves vertically with the sash but is permitted to move laterally relative to the sash. Within the U-shaped member is positioned a resilient member bent into what may best be described as a wavy formation. Such member is held in place by the sides of the U-shaped member and tensions the edge of the U-shaped member away from the edge of the sash plate. With such a construction a certain amount of resiliency is given to the edge of the sash, but the transverse movement of the sashes within the jamb remains limited within reasonable bounds. Further, having the sash plate a stiff, substantially straight member tends to prevent it from catching on inequalities in the jamb partition against which it rubs.

This invention can readily be understood by reference to the accompanying drawing illustrating the same, in which Fig. 1 is a face view of a sash with the jamb partition against which it strikes shown in section as indicated by line 1—1 of Fig. 3; Fig. 2 is a perspective view of the resilient member, and Fig. 3 is a section on line 3—3 of Fig. 1.

In these drawings, the numeral 10 designates the sash having a plate 12 which extends through an opening 14 in the jamb wall toward the partition 16. A U-shaped

member 18 fits around the edge of the plate 12, and within the U-shaped member 18 is positioned the member 20 which is flat in the plane of the sash plate but is formed in waves to tension member 18 away from the edge 55 of the plate 12. In the example here shown member 20 is provided with a bottom hook 22 to support the bottom of U-shaped member 18, and at the top is bent over to form the projection 24 which extends over the top of 60 plate 12 and is held in place by the sash chain 26.

It is to be understood that this example is given only by way of illustration and may be modified within the spirit of my invention. 65

What I claim is:

In combination with a sash having an edge plate adapted to extend through an opening into a jamb, a U-shaped member adapted to embrace the edge of the sash and movable 70 laterally relative to the sash and a resilient member within said U-shaped member to hold the closed edge thereof tensioned away from the edge of the sash, said resilient member having its top connected with the sash 75 and its bottom part being shaped to support said U-shaped member.
